PERPETUAL CALENDARS

James E. Lewis, 3219 N. Panama, Chicago 34, Ill.

Filed May 31, 1960, Ser. No. 32,983

12 Claims. (Cl. 40—114)

This invention relates to a calendar, particularly a perpetual calendar of the kind adapted to show the date of any day of any selected year.

Oftentimes it is desired to determine particular information about a certain year or group of years. For example, it may be important to be able to find the day of the week for any date in a certain year. As a further example it may be desirable to determine all of the months beginning on Sunday in a particular year.

Various systems and arrangements for a perpetual calendar have heretofore been proposed. Thus, complex formulas have been derived and elaborate charts and the like have been developed in attempts to provide information of this sort. However, the formulas, charts and the like as heretofore proposed have generally required a complicated manipulation or procedure for each item of information obtained. Consequently, the formulas, charts and the like heretofore proposed have had limited utility, and the information obtained has been inherently subject to error by reason of the complicated process required for extracting the information. Moreover, the formulas, charts and the like as heretofore proposed oftentimes are valid and accurate for only a certain span of years.

It is therefore a primary object of the present invention to enable a complete calendar for any selected year to be viewed in its entirety at one time. It is a related object to show simultaneously the dates for all of the days of any selected year in a conventional calendar formula.

It is a further object of the present invention to construct a perpetual calendar that once set for any selected year need not be reset. Thus, any desired calendar information for a particular year can be determined visually and without necessity of resorting to separate manipulations of calculations for different items of information for any selected year.

It is another object of the present invention to construct a perpetual calendar which is effective to function in this manner and which is entirely mechanical in nature. It is a corollary object to enable a perpetual calendar to be quickly and easily reset for any selected year.

A calendar constructed in accordance with the present invention includes a plurality of heptagonal faced rods arranged in groups corresponding to the twelve months of a year. There are sufficient rods in each group for presenting all possible weeks in any month, and each face of each rod is divided into seven longitudinally aligned divisions for the seven days of a week. Reference numerals for indicating the date of the day of the week are formed in predetermined ones of these divisions. The rods are disposed closely adjacent viewing apertures formed in a cover plate of the perpetual calendar. The

2

viewing apertures are substantially coextensive in length with a face on a rod and are marked with month and day identifying data. Also, the viewing apertures are effective to permit only one face or rod to be viewed in any one time. The rods are interconnected for rotation with one another and in equal angular amounts about their respective longitudinal axes so that the rods can be rotated to enable different combinations of rod faces, corresponding to different years, to be coordinately presented for view. The perpetual calendar of the present invention also includes mechanism for selectively rotating the rods allocated to March through December one-seventh of a complete turn with respect to the rods allocated to January and February to vary the starting dates of the months of March through December by one day to compensate for leap years. To set the calendar incorporating this heptagonal-faced rod arrangement for any selected year, the operator need know only the day of the week that the year starts on and whether the year is a leap year or a common year. This latter information can be directly obtained from a chart listing this information opposite a chronological arrangement of years. With this information in mind the calendar can be set for the selected year in a quite simple manner merely by rotating the rod allocated to the first week in January to present the proper face to view at the corresponding viewing apertures, and, if necessary, making a slight additional compensation for a leap year setting. Inasmuch as all of the remaining rods of the calendar are trained for rotation with the rod allocated for the first week in January, rotation of this one rod is effective to set up the complete calendar for the selected year. Moreover, once the calendar is initially set for any selected year, the calendar need not be reset to determine any other information for the entire year. It is another object of the present invention to incorporate the foregoing structural features effective to function in the manner described in a novel perpetual calendar.

It is still a further object of the present invention to incorporate a mechanism for visually indicating whether a leap year or a common year has been selected in a perpetual calendar which incorporates the foregoing structural features.

Other and further objects of the present invention will be apparent from the following description and claims and are illustrated in the accompanying drawings which, by way of illustration, show a preferred embodiment of the present invention and the principles thereof and what is now considered to be the best mode contemplated for applying these principles. Other embodiments of the invention embodying the same or equivalent principles may be used and structural changes may be made as desired by those skilled in the art without departing from the present invention and the purview of the appended claims.

In the drawings:

Fig. 1 is a plan view, partially broken away in parts to show details of construction, of a perpetual calendar constructed in accordance with one embodiment of the present invention;

Fig. 2 is a side elevation view taken approximately along the partially offset line indicated by the arrows 2—2 in Fig. 1;

Fig. 3 is a perspective view illustrating a frame assembly incorporated in the perpetual calendar illustrated in Fig. 1 and indicates the manner in which rod members are mounted in and supported for rotation in the frame assembly.

Fig. 4 is an elevation view in section taken substantially along the line indicated by the arrows 4—4 in Fig. 1;

Fig. 5 is an elevation view taken substantially along the line indicated by the arrows 5—5 in Fig. 4;

Fig. 6 is a fragmentary elevation view in section taken substantially along the line indicated by and in the direction of the arrows 6—6 in Fig. 4;

Fig. 7 is a fragmentary elevation view in section taken substantially along the line indicated by and in the direction of arrows 7—7 in Fig. 4;

Fig. 8 is a perspective view of a rod member incorporated in the calendar illustrated in Fig. 1;

Fig. 9 is a view of a part of a chart which may be utilized in conjunction with the perpetual calendar illustrated in Fig. 1 to determine the day of the week on which any selected year starts as well as whether the selected year is a common year or a leap year;

Fig. 10 is a chart showing the fourteen different combinations of rod faces for the calendar illustrated in Fig. 1 for any and all set-ups;

Figs. 11—20 are layout views of the different rods utilized in the calendar illustrated in Fig. 1; and

Fig. 21 is a somewhat schematic view of mechanism of visually indicating whether a leap year or common year has been selected in the calendar illustrated in Fig. 1.

In Fig. 1 a perpetual calendar constructed in accordance with one embodiment of the present invention is indicated generally by the reference numeral 31. In this instance the calendar 31 is arranged to present the twelve months of a year in a format of three groups of four months each. Thus, January, February, March, and April are aligned horizontally in the top group of months while May, June, July, and August are included in the center group and September, October, November, and December are included in the lower group. This format enables a compact mechanism to be obtained. However, as will become more apparent from the description to follow, other formats can equally well be utilized. Thus, by way of example, the twelve months of a year could be vertically aligned with respect to one another if so desired.

In Fig. 1 the calendar 31 is shown as set up for the leap year 1960, and it will be apparent from an inspection of Fig. 1 that the date of each day of the year is clearly visible in a conventional week-by-week arrangement.

With reference to Figs. 2 and 3 as well as the broken away portions of Fig. 1, it is seen that the calendar 31 includes a frame assembly 32 which includes a bottom plate 33 and a pair of side rails 34 and 36 affixed thereto. The side rails 34 and 36 are preferably removably secured to the bottom plate 33 in any suitable manner, such as by screws or the like, and reinforcing angles 37 and 38 are attached to the respective side rails 34 and 36 and the bottom plate 33 at the juncture of the side rails with the bottom plate. Each side rail is formed with a plurality of equally spaced circular apertures 39 which are aligned with corresponding apertures 39 in the opposite side rail. In the form of the invention illustrated in Figs. 1—3, each side rail is formed with eighteen such apertures, and these apertures are effective to support heptagonal-faced rod members for rotation therein. Thus, a rod member as 41 (see Fig. 3) is formed with supporting stubs 42 and 43 which project from the opposite ends thereof and which are adapted to fit within an aligned pair of apertures 39 in the side rails 34 and 36.

The frame assembly 32 also includes a center rail 46 which is suitably affixed to the bottom plate 33 and which extends longitudinally between the first six pairs of aligned apertures 39 in the side rails 34 and 36. The center rail 46 is additionally formed with apertures 47, each of which is aligned with a corresponding pair of aper-

tures 39 in the side rails 34 and 36. This construction enables pairs of heptagonal-faced rod members as 48 and 49 (see Fig. 3), each of which is half as long as a rod member 41, to be mounted for rotation between the side rails 34 and 36. Thus, a rod member 49 is formed with a projecting stub 51 at one end thereof and which is adapted to fit within an aperture 39 in the side rail 36. The opposite end of the rod member 49 is formed with a circular bore 52. The rod member 48 is formed with axially projecting stub shafts 53 and 54 at the opposite ends thereof. The stub shaft 53 is adapted to be received within an aperture 39 in the side rail 34 while the stub shaft 54 is adapted to project through an aperture 47 in the center rail 46 and fit within the circular bore 52 of the rod member 49 to thereby support both of the rod members 48 and 49 from the center rail 46.

The center rail 46 has been omitted in the broken away portion of Fig. 1 to simplify and clarify the showing of a drive connection between two rod members 48' and 49' presently to be described.

The entire frame assembly 32 is adapted to nest within an open-top container 56 which thus affords a protective and decorative exterior for the frame assembly 32.

The calendar 31 also includes a top-cover plate 57 which is positioned above the frame assembly 32 and associated rod members and which is suitably attached to the lower container 56 in any suitable manner. Thus, cap screws or like fastening devices, not illustrated in the drawings, can be utilized for this purpose. The cover plate 57 is formed with viewing apertures 60 which are marked with weekday identifying data and which are adapted to coat with corresponding faces on the rod members 41, 48, and 49 to present to view numerical calendar data carried on the faces of the rods in the manner illustrated in Fig. 1 and subsequently to be described in greater detail herein.

Each of the rod members 41, 48, and 49 is composed of individual rods longitudinally aligned with one another. Thus, the rod member 41 illustrated in Fig. 3 includes three individual rods, each designated by the numeral 6 and a fourth rod 6A. Likewise, the rods 48 and 49 illustrated in Fig. 3 are each composed of two individual rods, each designated by the numeral 4. In accordance with the present invention each of the twelve rod members 41, six rod members 48 and six rod members 49 is composed of different combinations of only ten separate and distinct rods, and these rods are designated by the numerals 1—6, 5A, 6A, 5B, and 6B in the layout views of Figs. 11—20. The characteristics of these individual rods will be described in greater detail hereinafter, but at this time it should be noted that the individual rods are to be incorporated in the rod members as 41, 48, and 49 in a predetermined manner whenever a side-by-side arrangement of months as illustrated in Fig. 1 is to be utilized.

In whatever arrangement of months is to be utilized in a perpetual calendar constructed in accordance with the present invention, individual rods as illustrated in Figs. 11—20 are arranged in groups corresponding to the twelve months of a year with sufficient rods in each group for presenting all possible weeks in any month. Thus, and as is apparent from an inspection of Fig. 1, it is possible to have days within six different weeks in the month of January. Accordingly, six rods, rods 1—6 shown in Figs. 13—18 respectively are allocated to the month of January. It is also possible to have days within six different weeks in each of the other months of the year with the exception of February. Inasmuch as February can have a maximum of only 29 days in any year, it is possible to have only days within five different weeks in the month of February regardless of the year involved. Therefore, only five rods are required for the month of February. However, in the side-by-side arrangement of the months in the form of the calendar illustrated in Fig. 1 an addi-

tional rod, rod 6B illustrated in Fig. 20, on which all the faces of the rod are blank, has been included for the month of February to facilitate mechanical construction of the calendar 31 as will become more apparent from the description to follow.

As noted hereinabove, respective Figs. 11-20 illustrate in layout view the individual rods incorporated in the calendar 31. In these figures the letters A-G are for descriptive reference only and are not included in an actual calendar mechanism. The relationship of the rods shown in Figs. 11-20 will best be appreciated by comparing the rods illustrated in Figs. 11-20 with the perspective view of the rod member 41 illustrated in Fig. 8. Thus, the rod member 41 illustrated in Fig. 8 is a solid one-piece member composed of four individual rods 1 each having numerically marked faces as illustrated in Fig. 13 of the drawings. Each rod 1 in the rod member 41 includes seven faces designated by the respective reference numerals A-G in Fig. 13. In this instance the rod member 41 provides the individual rods 1 for the first weeks of each of the months of May, June, July, and August in the calendar 31 illustrated in Fig. 1. For the year 1960 face G of the rod 1 allocated to the first week in May is presented to view in the aperture 60. Likewise the face D of the rod 1 allocated to the first week in June is presented to view, and the faces B and F of the respective rods 1 allocated to the first weeks in the respective months July and August are presented to view.

Each face of each rod is formed with seven divisions corresponding to the seven days of a week and the given date numeral for each of the seven days of the week is afforded by the arrangement of the numerals in the divisions of the respective faces of the rods as will be apparent from an inspection of Figs. 11 through 20. Thus, by a proper selection of the individual rods and proper orientation of the rods in each month by group, all of the numbered days in a month can be shown in serial order regardless of the day of the week on which the month starts. By way of example, January which has thirty-one days, requires one each of the rods 1 through 6 illustrated in the respective Figs. 13-18. The six rods thus allocated to January are initially orientated with respect to one another so that corresponding faces of each of the rods are simultaneously presented for view at the aperture 60 in the manner illustrated in Fig. 1. Each of the months of March, May, July, August, October, and December also have thirty-one days and therefore require the same rods 1 through 6 as allocated to the month of January. The months of April, June, September, and November have only thirty days. For these months appropriate rods 5A and 6A, shown in respective Figs. 11 and 12, which are marked for a 30-day month rather than a 31-day month are associated with rods 1 through 4 illustrated in respective Figs. 13-16. In the case of February which has twenty-eight days in a common year or twenty-nine days in a leap year, rods 5B and 6B as illustrated in Figs. 19 and 20 are associated with rods 1-4. In the case of rod 5B the 29th day of February has been designated by the reference character L rather than a numeral 29 to minimize any possible conflict with the first day of March in the case of a common year or non-leap year. Also, and as noted hereinabove, since February cannot have more than five weeks, all seven faces of the rod 6B are blank.

In accordance with the present invention operating means are included in the calendar 31 for rotating the rods allocated to the respective months in unison and in equal angular amounts about their respective longitudinal axes to present different combinations of rod faces, corresponding to different years, in viewing position at the apertures 60 in the cover plate 57. With reference to the broken away showing in Fig. 1 as well as Fig. 2, it is seen that the operating means include sprockets 66 which are suitably fixed for rotation with

the rod members 41 and 49, as by being keyed on the stub shafts 43 and 51. A chain belt 67 is engaged with each of the sprockets 66, and inasmuch as each of the sprockets 66 has the same diameter and has the same number of sprocket teeth as any other sprocket 66, rotation of any one sprocket, as by knurled knob 68 (see Fig. 1), is effective to rotate each of the other sprockets an equal amount. Thus, each of the rod members 41 and 49, corresponding to the months of March through December, are adapted at all times to be rotated with one another in either direction of rotation.

The rod members 48, corresponding to the months of January and February, are also connected for rotation with the rod members 41 and 49 and in equal angular amounts therewith. However, the means affording the connection between the rods allocated to the months of March and April and the months of January and February include a lost-motion connection which permits one-seventh of a turn of relative rotation between the rods allocated to the months of January and February and the rods allocated to the remaining months of the year to compensate for leap years as will now be described.

With particular reference to Figs. 4-7, it is seen that the above-noted lost-motion connection is afforded by a pin and slot construction associated with the rod members 48' and 49' which comprise the respective rods 1 allocated to the first week in each of the months of January, February, March and April. In this instance the adjacent ends of the rod members 48' and 49' include disk members 71 and 72. The disk member 71 is formed with an arcuate slot 73 extending through an angle of substantially 51 degrees. A pin 74 projects from the disk member 72 sufficiently far to have the free end thereof disposed within the slot 73 so as to be engageable with the end surfaces of the slots 73. It will thus be apparent from an inspection of Figs. 4-7 that, depending upon the initial disposition of the pin 74 within the slot 73 and the direction of rotation of the rod member 49', the rod member 49' may be rotated one-seventh of a turn relative to the rod member 48' prior to producing any rotation of the rod member 48'.

Each of the remaining rod members 48, which are composed of the remaining rods allocated to the respective months of January and February, are connected for rotation with the rod member 48' by a series of sprockets 76 and a link belt 77 similar to the sprockets 66 and link belt 67 described hereinabove with reference to the mechanism for rotating the rod members 41 with the rod members 49.

The calendar 31 of the present invention is adapted to be set for any selected year by rotating the knurled knob 68 in a clockwise direction, as viewed from the right side of the calendar 31 illustrated in Fig. 1, to position the proper face of the rod 1 allocated to the first week in January at the viewing aperture 60. Thus, for either a common year or leap year the knob 68 is rotated in the above noted clockwise direction until the numeral 1 is positioned beneath the proper day of the week for the selected year. Each of the rods of the calendar 31 is trained for rotation with the rod 1 allocated to the first week in January through the sprocket and belt mechanism noted hereinabove so that in the case of a common year rotation of the rods through the operating knob 68 is effective automatically to position each of the other rods with a proper face at the respective viewing apertures 60. Thus, since in the case of a common year, a year must start on a given day of the week, seven different combinations of rod faces at the viewing apertures 60 suffice for any possible common or non-leap year calendar. However, in the case of a leap year, in which the month of February has one extra day, the starting dates of each of the months of March to April are delayed by one day. The lost-motion connection afforded between the rods allocated to months of January and

February and the rods allocated to the remaining months of the year enable the necessary shifting of the numeral dates of the months of March through December to be obtained. That is, the one-seventh of a turn of relative rotation afforded by the pin and slot connection 74 and 73, described in detail hereinabove, enables each of the rods allocated to the months of March through December to be rotated one-seventh of a turn in a counterclockwise direction, as viewed from the right end of the calendar 31 illustrated in Fig. 1, to shift the numeral dates for each of the days in these months by one day to compensate for the extra day included in the month of February in a leap year.

Thus, one additional combination of rod faces can be effected for each of the above-noted seven combinations, so that a total of fourteen different combinations of rod faces at the viewing apertures 60 suffice for any and all year set-ups. The fourteen possible combinations of rod faces for rod 1 of each month have been charted in Fig. 10 wherein the combination of rod faces corresponding to the leap year 1960 is set out in the line numbered 9. By comparing Figs. 1 and 10 it can be seen that the relative disposition of the rod faces indicated in Fig. 1 corresponds to that set out in line 9 of the chart in Fig. 10. Thus, once the individual rods have been initially oriented with respect to one another in the manner illustrated in Fig. 1 and connected for rotation in the manner described hereinabove, it is necessary to know only two facts to reset the calendar for any selected year. The day of the week that the year starts on must be known, and it must be known whether the year is a leap year or a common year. Both of these factors can be read directly from a chart, as illustrated in Fig. 9, wherein the starting date of the week of the year and the designation of the year as a leap or a common year is positioned beside a chronological listing of years.

In brief summary the operation of the calendar 31 is as follows: the starting date of the week of the particular year to be set on the calendar 31 as well as the designation of the year as a common year or a leap year is determined, as by having reference to a chart like that illustrated in Fig. 9. The control knob 68 is rotated in a clockwise direction as aforesaid to set the date January 1 in alignment with the proper day of the week. If the year is a common year no further manipulation of the calendar 31 is required, and the correct dates for each day of the selected year are shown simultaneously in a conventional week-by-week calendar format. However, if the year is a leap year, the control knob 68 is subsequently rotated one-seventh of a turn in a counterclockwise direction as aforesaid to rotate the rods allocated to the months of March through December one-seventh of a turn and thereby shift the numeral dates of each of the days of the months of March through December by one division to compensate for the extra day and the month of February while the settings for January and February remain undisturbed. After this slight adjustment of the calendar 31 to compensate for the leap year, no further manipulation of the calendar 31 is required. When it is thereafter desired to reset the calendar 31 for some other year, the control knob 68 is again rotated in a clockwise direction. In no case will it be necessary to rotate the control knob 68 more than six-sevenths of a complete turn. The maximum amount of rotation that is required of the control knob 68 is that necessary to reset the calendar for the next succeeding year, in which case it is necessary to rotate the control knob 68 six-sevenths of a turn.

Thus, to reset the calendar 31 from the set-up from the year 1960 to the set-up for the year 1961, the knob 68 is rotated in a clockwise direction six-sevenths of a turn. This has the effect of rotating the rod 1 allocated to the first week in January through five-sevenths of a turn since one-seventh of a turn of relative rotation between the rods 1 allocated to the months of March and

April and the rods 1 allocated to the months of January and February is permitted by reason of the lost-motion connection therebetween prior to any rotation of the rods 1 allocated to the first weeks in January and February. Thus, face B of the rod allocated to the first week in January is shifted from beneath the aperture 60 and the face G is shifted into view, as will be apparent from an inspection of Fig. 13. The numeral 1 on the face G of rod 1 is thereby positioned for the starting 10 day of the week (Sunday) of the year 1961. Inasmuch as the rod 1 allocated to the first week in March is rotated six-sevenths of a turn, face E is shifted from view and face D is shifted into viewing position at the aperture 60. With reference to Fig. 13 it will be noted that this is the proper face for the first week of March in the year 1961. The proper faces of each of the other rods of the calendar 31 are likewise positioned at the viewing apertures 60 by the above-described clockwise rotation of the control knob 68.

20 In accordance with the present invention retaining means are preferably included in the perpetual calendar 31 for retaining the calendar in any selected yearly set-up. With particular reference to Figs. 4-7 one form of retaining means is shown as including a spring-type latching detent 81 of a V-shaped configuration in which the apex of the V is adapted to seat within complementary shaped notches 82 formed in the periphery of the disk member 71.

Also, means are preferably included in the calendar 31 30 for visually indicating whether the calendar is set up for a common year or a leap year. As illustrated in Fig. 1 the indicator means are designated generally by the reference numeral 86 and include an arcuate-shaped cutout or window 87 formed in the cover plate 57 beneath which a pointer 88 is swingable to indicate either a leap year or a common year.

With particular reference to Fig. 21, one form of a mechanism for accomplishing swinging movement of the pointer 88 is illustrated. Thus, the outermost end portion of the rod member 49' is formed with external threads 89 of relatively high pitch and includes a washer 91 suitably attached thereon as by a cap screw 92. The control knob 68 is movable axially on the threads 89 in a direction dependent upon the direction of rotation 40 of the control knob. Thus, with a standard right-hand thread, rotation of the control knob 68 in a clockwise direction, in the course of setting a common year in the manner described hereinabove, causes the control knob 68 to move leftwardly and in a rapid manner by reason 45 of the relatively high pitch of the threads 89, as viewed in Fig. 1, and into engagement with the shoulder afforded at the inner end of the threads 89. The pointer 88 is pivoted for rotation about a fulcrum 93, and a follower member 94 is connected to the pointer 88 and biased 50 toward engagement with the control knob 68 as by a spring 96. Thus, the inclination of the pointer 88 is dependent upon the axial position of the control knob 68 on the threaded end 89 of the rod member 49, so that rotation of the control knob 68 in a clockwise 55 direction moves the pointer 88 to indicate a common year setting while rotation of the control knob 68 in a counterclockwise direction, and outwardly on the threads 89, enables the pointer 88 to swing to the leap year designation.

60 Hence, while I have illustrated and described the preferred embodiment of my invention, it is to be understood that this is capable of variation and modification, and I therefore do not wish to be limited to the precise details set forth, but desire to avail myself of such 65 changes and alterations as fall within the purview of the following claims.

I claim:

1. A perpetual calendar for simultaneously showing a complete calendar for any selected year and comprising a plurality of heptagonal-faced rods arranged in

groups corresponding to the twelve months of a year, operating means for rotating the rods to present to view different combinations of rod faces corresponding to different years, and means affording substantially one-seventh of a turn of relative rotation between the rods allocated to the months of January and February and the rods allocated to the remaining months of the year to compensate for leap years.

2. A perpetual calendar for simultaneously showing a complete calendar including the dates of all of the days of any selected year and comprising a plurality of heptagonal-faced rods arranged in groups corresponding to the twelve months of a year, operating means interconnecting the rods for rotation with one another and in equal angular amounts about their respective longitudinal axes to disposed one face of each rod in a predetermined angular disposition in the calendar and thereby enable different combinations of rod faces corresponding to different years to be coordinately presented for view, and means affording a lost-motion connection between the rods allocated to the months of January and February and the rods allocated to the remaining months of the year for enabling the rods allocated to March through December to be rotated one-seventh of a complete turn with respect to the rods allocated to January and February to compensate for leap years.

3. A perpetual calendar for simultaneously showing a complete calendar including the dates of all of the days of any selected year and comprising a plurality of heptagonal-faced rods arranged in groups corresponding to the twelve months of a year, operating means interconnecting the rods for rotation with one another and in equal angular amounts about their respective longitudinal axes to place one face of each rod in a predetermined angular disposition in the calendar and thereby enable different combinations of rod faces corresponding to different years to be coordinately presented for view, whereby seven different combinations of rod faces, corresponding to the seven days of a week on which a common year can start, can be obtained, and means for compensating for leap years, said means including a lost-motion connection between the rods allocated to the months of January and February and the rods allocated to the remaining months of the year for enabling the rods allocated to March through December to be rotated one-seventh of a complete turn with respect to the rods allocated to January and February to compensate for leap years, whereby one additional combination of rod faces can be effected for each of the above-noted seven combinations, so that a total of fourteen different combinations of rod faces suffice for any and all yearly set-ups.

4. A perpetual calendar for simultaneously showing the dates of all of the days of any selected year and comprising a plurality of heptagonal-faced rods arranged in groups corresponding to the twelve months of a year, operating means interconnecting the rods for rotation with one another and in equal angular amounts about their respective longitudinal axes to position one face of each rod in a predetermined angular disposition in the calendar and thereby enable different combinations of rod faces corresponding to different years to be coordinately presented for view, means for compensating for leap years, said means including a lost-motion connection affording one-seventh of a complete turn of relative rotation between the rods allocated to the months of January and February and the rods allocated to the remaining months of the year, and indicator means associated with said operating means for indicating whether a common year or a leap year has been selected.

5. A perpetual calendar as defined in claim 4 including latching means for retaining the calendar in any selected set-up.

6. A perpetual calendar for simultaneously showing in

a conventional week-by-week calendar format the dates of all of the days of any selected year, said perpetual calendar comprising a plurality of rods each formed with seven longitudinally extending faces divided in seven divisions for the seven days of a week and having reference numerals in predetermined ones of said divisions, said rods being arranged in groups corresponding to the twelve months of a year with sufficient rods in each group for presenting all possible weeks in any month, cover means for disclosing to view all but one face of each rod, said cover means having viewing apertures formed therein generally coextensive in length with a face on a rod and marked with month and day identifying data, operating means for rotating the rods in unison equal angular amounts about their respective longitudinal axes to present different combinations of rod faces corresponding to different years in viewing position at said apertures, and compensating means for selectively rotating the rods allocated to March through December one-seventh of a complete turn with respect to the rods allocated to January and February to vary the starting dates of March through December one day to compensate for leap years.

7. A perpetual calendar as defined in claim 6 wherein at least five rods are allocated to February and six rods are allocated to each of the other months.

8. A perpetual calendar as defined in claim 6 wherein the rods are arranged to present the twelve months in a format of three vertically disposed groups of months with four horizontally aligned months in each group of months with adjacent ends of rods allocated to given months in each four month group joined together except for said lost-motion connection between the rods allocated to March and February.

9. A calendar for simultaneously showing the dates of all of the days of any selected year and comprising a plurality of heptagonal-faced rods arranged in groups corresponding to the twelve months of a year, frame means mounting the rods for rotation about their longitudinal axes, operating means interconnecting the rods for rotation with one another and in equal angular amounts about their respective longitudinal axes to place one face of each rod in a predetermined angular disposition in the calendar and thereby enable different combinations of rod faces corresponding to different years to be coordinately presented for view, and compensating means for selectively rotating the rods allocated to March through December one-seventh of a complete turn with respect to the rods allocated to January through February to vary the starting dates of March through December one day to compensate for leap years.

10. A perpetual calendar as defined in claim 9 wherein the operating means include sprocket and link belt means interconnecting said rods for rotation with one another.

11. A perpetual calendar as defined in claim 9 wherein the compensating means include a pin and slot connection between one of the rods allocated to March and a corresponding rod allocated to February.

12. A perpetual calendar for simultaneously showing the dates of all of the days of any selected year, said perpetual calendar comprising a plurality of rods each formed with seven longitudinally extending faces divided in seven divisions for the seven days of a week and having reference numerals formed in predetermined ones of said divisions, said rods being arranged in groups corresponding to the twelve months of a year with sufficient rods in each group for presenting all possible weeks in any month, frame means mounting said rods for rotation in said calendar and effective to align one face of each rod in substantially a common plane, cover means for disclosing to view only said one face of each rod, said cover means having viewing apertures formed therein generally coextensive in length with a face on a rod and marked with month and day identifying data, operating means for rotating the rods in unison equal angular amounts

about their respective longitudinal axes to present dif-

ferent combinations of rod faces corresponding to different years in viewing position at said apertures, and compensating means for selectively rotating the rods allocated to March through December one-seventh of a complete turn with respect to the rods allocated to January through February to vary the starting dates of March through December one day to compensate for leap years.
